UNITED STATES PATENT OFFICE.

RICHARD C. STEWART, OF COVINGTON, KENTUCKY, ASSIGNOR TO THE STEWART IRON WORKS COMPANY, OF COVINGTON, KENTUCKY, A CORPORATION OF KENTUCKY.

STARTING DEVICE FOR RACE TRACKS.

Application filed December 27, 1927. Serial No. 242,615.

In starting races at race-tracks it has heretofore been a difficult matter to line up the horses for proper starting, resulting in many false starts. It has also heretofore been the 5 experience that horses and jockeys have been injured in efforts to properly line up or position the horses for starting, and thoroughbred horses have been injured by the rearing or plunging of themselves or their companions in efforts to obtain proper starts.

It is the object of my invention to provide means whereby injury to horse or jockey due to the reasons mentioned may be minimized or avoided; further, to provide novel means 15 for positioning the horses for starting in the race and for removing obstructing portions of the positioning means away from the track for preventing interference thereof with the race; further, to provide movable partitions 20 for forming stalls at the race-track, and means for moving said partitions quickly for non-interference with the race; further, to provide means for suspending the partitions and moving the partitions crosswise of the 25 track to form stalls in which the horses may be placed so as to be headed lengthwise of the track; further, to provide means for quickly moving the partitions laterally away from the running part of the track; further, 30 to provide means whereby to raise and lower the partitions with relation to the running surface of the track; further, to provide novel means for laterally positioning the partitions for forming the stalls arranged 35 crosswise of the track; further, to provide novel means for limiting relative movement between the partitions for forming the stalls; further, to provide novel means whereby to 40 control the number of stalls arranged crosswise of the track; and, further, to provide novel means to arrange the partitions with relation to the crosswise inclination of the track.

While I show and describe my invention as 45 applicable to horse racing, it will be readily understood that the same is applicable to racing of other characters, for instance of dogs and other racing animals.

The invention will be further readily understood from the following description and claims, and from the drawings, in which latter:

Fig. 1 is a front elevation of my improved device shown in set-up relation.

Fig. 2 is a similar view, partly broken

away, showing the stalls in retracted positions.

Fig. 3 is an end view of my improved device, viewed from the operating end, and partly broken away.

Fig. 4 is a central vertical longitudinal section of a detail of the take-up end of the same.

Fig. 5 is a vertical cross-section of my improved device, taken in the plane of the line 5-5 of Fig. 1, and partly broken away.

Fig. 6 is a vertical cross-section of a detail of the same, taken on the line 6-6 of Fig. 1.

Fig. 7 is a vertical longitudinal section of a detail of the same, taken in the plane of the line 7-7 of Fig. 6.

Fig. 8 is a front elevation of a detail of the limiting means for the partitions.

Fig. 9 is a horizontal section of a detail of the partition, taken on the line 9-9 of Fig. 5.

Fig. 10 is a cross-section of a detail of the suspending means for the girder, taken on the line 10-10 of Fig. 1.

Fig. 11 is a rear view of a detail of the stalls.

Fig. 12 is a front elevation of my improved device, showing a modification of the same; and

Fig. 13 is a cross-section of the same, taken on the line 13-13 of Fig. 12.

The race-track is shown at 21, which represents the roadway along which the horses move. At the respective sides of the track there is usually an outer rail 22 and an inner rail 23. This would place the judges' stand at the right in Fig. 1, and the grand stand at the left in Fig. 1, assuming that the starting point and the finishing point of the race is the same.

The roadway of the track is usually inclined or banked in round or oval courses, or in fact all race courses other than straight-away courses. The inclination of the running surface of the track is upwardly toward the outer side of the track, this inclination varying according to the curvatures of the various portions of the track, the rule being usually that the shorter the curvature the greater the inclination.

My invention contemplates the temporary arrangement of stalls crosswise of the track, so arranged that the same may be employed for the start of the race, and may be quickly moved out of the way of the running portion of the track, in order that if the race passes my improved device, this may be done.

without obstruction or interference with the race.

I provide a bridge which spans the roadway and along which partitions are suspended and moved and placed in proper positions crosswise of the track to form stalls, and which may be quickly moved out of the way after the start of the race for non-interference with the race.

10 In the present exemplification, I provide posts 25, 26, at the respective sides of the track, shown imbedded in concrete foundations 27, 28, located in the ground. The posts have a girder 29 between them which 15 spans the track. It is located sufficiently high above the track to provide for proper head clearance for the horses and jockeys and the devices between the latter and the girder, and for avoiding undue obstruction 20 to the vision of the spectators. This girder is shown as a truss structure, comprising a lower channel iron 31, and an upper inverted channel iron 32, the side wings of the channel irons being rigidly connected by suitable truss bars 33 for forming the truss structure. The respective ends of the girder are rigidly 25 connected with the posts, as by means of flange-plates 34, 35.

30 Partitions 41 are arranged to be moved lengthwise of the girder to form stalls 42, and means are provided for holding the partitions in place with sufficient firmness to permit entry of the horses into the stalls and for location of the horses in the stalls, and to resist movements of the horses while in the 35 stalls. For accomplishing this the lower ends of the partitions are connected with the roadway. The partitions are permitted vertical movement for this purpose. This vertical movement in the present exemplification 40 is obtained by movement of the support on which the partitions are guided into their respective lateral positions.

45 This support is in the form of a runway 44, which extends lengthwise of the girder and is supported from the girder and is arranged to be moved up and down with relation to the girder. The runway is shown of inverted U-form in cross-section provided with lower 50 flanges 45 having inner up-turned edges 46, for forming channels 47 in which the wheels 48 of carriers 49 are arranged to travel. These carriers support the partitions. The 55 upper wall of the runway retains the wheels in the channels.

The runway extends lengthwise of the girder and is guided laterally with relation to the girder by guide-strips 51, 52, fixed to the girder and depending therefrom at the respective sides of the runway.

60 A shaft 55 extends lengthwise of the girder, and is supported in suitable bearings, suitably placed in sufficient number along the length of the shaft to properly support the shaft. 65 The shaft is exemplified as a hollow tube.

The bearings are shown as rollers 56 at the respective sides of the shaft, forming a depression in which the shaft is supported. Each of the rollers is mounted on an axle 57 journaled in ball-bearings 58 on a bearing-block 70 75 59 fixed in the hollow of the girder. The runway extends throughout the length of desired travel of the partitions and the shaft extends substantially throughout the length of the runway.

At suitable points lengthwise of the shaft it is provided with sheaves 61 fixed to the shaft. Cables 62 are received about the sheaves. One end of each of the cables is fixed to its sheave, the other end of the cable being fixed to the runway, as by having the ends of its strands spread and suitably leaded in the socket 63 of a socket-piece 64 fixed to the runway.

85 A worm-wheel 65 is fixed to the shaft, and is meshed by a worm 66, fixed to a shaft 67. The shaft 67 is journaled in bearings 68, 69, in the girder, and in a bearing 70, the shaft being provided with an operating handle 71, for manual operation of the shaft, although it is obvious that an electric motor or other power means may be substituted therefor. Endwise movement of the shaft 67 is prevented by the location and arrangement of the bearings 68, 69, in connection therewith and with the worm.

90 The bearings 56 and the cables 62 are so distributed lengthwise of the girder as to properly support the shaft and to properly support the runway and prevent undue sagging of either. The cables 62 pass through holes 72 in the bottom wall of the girder.

95 The girder is preferably provided with intermediate supports, exemplified as tie-members 73, which may be tie-rods or cables, secured at their upper ends to the upper ends of the posts, as at 76, and secured at their lower ends to the girder at various positions lengthwise of the girder. This latter connection may be by means of a fork 77 pivoted to pins 78 received through holes in the girder, and having the lower end of the tie-member connected therewith by providing said lower end with a ring 79, received between the upper ends of the fork-members and connected thereto by a pivot-pin 80. A turn-buckle 81 is arranged to have threaded connection with the threaded adjacent ends 82, 83, of sections of the tie-member.

100 The carriers 49 are exemplified as comprising a frame 85, having bearings 86 shown as ball-bearings therein, in which the axles 87 of the wheels 48 rotate, the wheels being fixed to the axles. A hanger-rod 88 is suspended from the carrier, and preferably has a slight pivotal movement with relation to the carrier, being shown received in a slot 89 in the carrier and pivoted in said slot by a pivot-pin 90. The hanger-rod has connection with the partition, and this connection is prefera- 105 110 115 120 125 130

bly at the center of gravity of the partition, so that the hanger may be suspended from its carrier and the carrier may travel readily upon its runway without binding stresses.

5 The pivotal connection of the partition with its carrier is provided to maintain the partition vertical during inclined position of the runway and regardless of crosswise inclination of the track.

10 The means for moving the partitions laterally are represented as a cable 91, fixed to one of the partitions, as by a clamp connection 92. The cable is exemplified as an endless cable, and is arranged to pass loopwise several times

15 about an operating sheave 93, for forming proper frictional connection with the operating sheave for travel of the cable upon rotation of the operating sheave. The operating sheave is shown fixed to an axle 94, journaled in bearings 95, on brackets 96 extending from one of the posts. The sheave is provided with a gear 97 with which a pinion 98 meshes. The pinion is on an operating shaft 99, journaled in bearings 100 in the brackets

20 96. An operating handle 101 is suitably connected with the shaft 99 for manual operation of the shaft, although it is obvious that power operation, for instance by means of an electric motor, may be substituted there-

25 for.

The cable also passes about a pulley 105 on an axle 106 journaled in bearings 107 on brackets 108 fixed to the post 26. The cable also passes in the form of a transverse stretch

30 35 111 lengthwise of the girder, preferably inside the girder, and at the other end of the girder passes over a pulley 112 on an axle 113 received in bearings 114 of brackets 115 fixed to the post 25. The cable then passes about an idler pulley 116 on an axle 117 received in bearings 118 of a fork 119, which has a tensioning weight 120 thereon for supplying tension to the entire cable and providing for proper stretched relation thereof.

40 45 The cable then passes about a pulley 121 on an axle 122 received in bearings 123 of hangers 124 at one end of the girder. These hangers are exemplified as fixed to the end of the runway 44.

50 55 The cable then passes as a crosswise stretch 125 lengthwise of the girder about a pulley 126 on an axle 127 received in bearings 128 in the brackets 108. The pulley 126 may be journaled on the runway if desired. It is preferably located below the runway for exerting downward stress upon the carriers. The cable then passes about the sheave. All of the bearings may be ball-bearings.

60 The sheave 93 is locked in its actuated positions by means of a latch 129 received in the tooth-spaces 130 in the gear 97.

The partitions are normally positioned in idle relation in the space 131 at the side of the track, passing through a gap 132, preferably 65 in the inside rail 28. The cable 91 is normal-

ly taut and the partitions are normally raised above the level of the ground.

The partitions are normally outside of the running course of the track. If a race is to be run, as many of the partitions as are required to provide a stall for each horse in the race are moved crosswise the track, there being preferably one extra stall provided for at the inner rail, which may be employed as a passageway by operatives at the track. A further passageway 133 may be provided at the other side of the track.

Distancing members are provided between the partitions to control the width of the stalls and to cause movements of successive partitions when the end partition, to which the cable is secured, is moved outwardly to form the stalls. Such distancing members are shown as a chain 141, which is secured along its length at points equaling the widths 85 of stalls to the hanger-rods 88 of each of the partitions, as by means of a bolt 142 received through one of the links of the chain and threaded into the hanger-rod.

Flexible connections 143 are also preferably provided at the rear ends of the stalls to keep the horses from backing out of the stalls. These flexible connections are shown as chains provided with snap-hooks 144 at their respective ends received in eyes 145 secured to the partitions.

Means are provided for locating the last partition employed in the forming of the stalls, exemplified as an arm 148, shown as a bent bar fixed to a shaft 149, journaled in 100 bearings 150 bracketed from the runway. The arm is provided with a handle 151. The arm and shaft form a lever. The arm is held endwise between the bearings 150, as by being fixed to the shaft and by providing the 105 shaft with shoulders 152 bearing endwise against the bearings 150. A spring 153 coiled about the shaft and having one end fixed to one of the bearings 150 and its other end received about the arm normally urges the arm 110 into interfering relation with the hanger-rods 88.

A flexible connection 154, for instance a cable, has an end 155 secured to the handle 151, and is received about direction pulleys 115 156, 157, on the girder, and has a depending end provided with securing means, for instance eyes 158, arranged to be selectively received about a hook 159 on the post 26.

The arm 148 is normally in interfering 120 relation with the hanger-rods 88. When the partitions are to be moved outwardly, the depending end of the cable is pulled and one of the eyes 158 fastened to the hook 159. As many of the partitions as are desired are 125 then moved outwardly until the second-last partition desired has passed the arm 148. The depending end of the cable is then released, the arm then automatically swinging 130 into interfering relation with a hanger-rod 130

88 of the last partition to be employed, and is maintained in interfering relation throughout the use of the stalls.

Upon operation of the sheave 93 for movement of the first partition to which the cable 91 is clamped, the said partition is moved with the cable toward the post 25, and as soon as the flexible connection 141, between said partition and the next partition becomes 10 taut, this next partition is caused to move, and following partitions are caused to move in the same manner, it being understood that during such movements the partitions are in the present exemplification raised 15 above the running surface of the track. When the arm 148 has been moved into interfering relation with the last partition to be employed in the arrangement of the stalls, and the flexible connections between the partitions are drawn taut, the latch 129 on the sheave 93 is latched to prevent the sheave from turning in either direction.

The partitions are thus held in suspended position at their proper locations. The runway 44 is thereupon lowered by rotation of the sheaves 61, this lowering being preferably performed rapidly so that the lower ends of the partitions are imbedded in the roadway for maintaining the lower ends of the partitions rigid with relation to the roadway. The lower ends of the partitions are provided with pointed ends 160 at their respective ends for this purpose.

The chains 143 are released at one of their ends and the horses led or ridden into the stalls, the chains being thereupon fastened to cross the rear ends of the horses to prevent the horses from backing out of the stalls.

A usual starting tape 161 is positioned at the front ends of the stalls, the respective ends of the starting tape being held by arms 162 at the respective sides of the track and the starting tape held taut between said arms. The arms are pivoted by pivots 163 to posts 164 at the respective sides of the track, and have extensions 165. Springs 166 have their respective ends secured to the ends of said extensions and to the posts, and normally urge the arms to swing outwardly and upwardly so as to snap the starting tape away from the front of the horses for the starting of the race. The arms are normally held in down position by means of usual latches 167, suitably electrically released in usual manner upon the pressing of an electric button.

The partitions are constructed to prevent interference between neighboring horses and to prevent injury to the horses and the jockeys. Each of the partitions preferably comprises a framing 171 of tubing. The sections of this tubing are suitably secured together, as by means of welding or in other desired manner. The partition comprises a lower section 172 having end walls 173, 174, a top wall 175 and a bottom wall 176, formed of

the tubing. The forward top corner is preferably rounded, as shown at 177. The end walls are preferably extended downwardly to form feet 178, which receive the spikes forming the pointed lower ends 160 of the partitions for ready entry into the running surface of the track. It may be explained that this running surface is usually readily penetrable for a number of inches, the spikes penetrating the running surface preferably for a number of inches for proper placement, and so that the lower wall 176 of the partition is located proximate to the running surface to prevent injury to the horses.

The inner portions of these walls are provided with slots 179 in which the edges of a panel 180 are received. This panel is shown composed of outer layers 181 of sheet metal and an intermediate layer 182 of wood, for forming a stiff and light panel for the partition. This forms a structure in which a smooth-faced panel is provided which merges into rounded edges to prevent injury to the horse or his rider.

A section 185 is provided above the section 172 at one end of the section 172, and preferably comprises meshed wires 186 secured in a frame 187, which is fastened to the walls of the section 185. These walls comprise the end wall 174 of the partition, an intermediate 95 hanger wall 188, one end of the wall 175 as a bottom wall, and a wall 189 at its top, the walls being rigidly connected together, as by welding, as heretofore stated.

The upper end of the front wall is braced, as by means of a transverse slanting member 190, to the hanger-rod 88, and rigidly connected therewith. This hanger-rod is shown as a continuation of the wall 188. The center of gravity of the structure is preferably in the line of the hanger-rod so that the partition is hung balanced from the carrier in front and rear direction.

In the exemplification of my invention shown in Fig. 1, the girder is shown parallel with the running surface of the track. In this example the runway is lowered to equal extent throughout its length. In the modification shown in Figs. 12 and 13, the girder is shown in a horizontal plane, the running surface of the track being at an inclination to the girder. The partitions are shown lowered to different extents to cause engagement between the lower ends of the partitions and the track, the runway being exemplified as lowered to different extents along its length for effecting such lowering of the partitions.

For accomplishing this I have exemplified the sheaves on the shaft 55 as of different diameters, as shown by the sheaves 611. The diameters of the sheaves increase toward the low side of the track. The cables 621 are of increasing lengths toward the low side of the track. These cables have their respective ends secured to the sheaves and to the run-

way in manner similar to the securing of the cables 62. It is desirable that the portions of the depending stretches received through the holes 72 in the girder depend in vertical 5 direction. Direction pulleys 191 rotatable in brackets 192 secured to the girder adjacent to the holes, are arranged to accomplish this. I have shown such a direction pulley at one side of the hole in Fig. 13, although it is obvious 10 that the pulley may be located at one side of said hole or at both sides of said holes.

When now the shaft 55 is turned for lowering the partitions, the sheaves being of different diameters lengthwise of the shaft, will 15 unwind portions of the cables of different lengths, so that as the cables are unwound the runway will assume a slanting position, in order that the lower ends of all of the partitions engage the runway of the track at 20 the same time, while the runway is securely supported throughout its length, due to the different diameters of the various sheaves and the different lengths of cables thereon.

When it is desired to raise the partitions, 25 the turning of the shaft 55 will raise the runway different extents throughout its length, for causing substantial parallelism between the runway and the girder when the runway has been raised.

30 The partitions are normally suspended in the space 131 between the rail at the side of the race-track and one of the posts. A bar 195 is provided to span the gap in the rail, the ends of the bar being received in slots 196 35 in the end posts 197 at said gap. This bar may be employed to confine the partitions in normal positions in the space 131. The arm 148 may be placed in interfering relation with the first partition so as to hold all of the 40 upper ends of the partitions in said space.

When it is desired to move the partitions for forming the stalls, the bar 195 is removed and the arm 148 is shifted into unobstructing 45 position and held by connection of one of the eyes 158 with the hook 159. The handle 101 of the winding unit is then turned for causing travel of the stretches of the cable along the overhead support. The lower stretch 125 of the cable is attached to the end one of the 50 partitions by the clamp 92.

Travel of the lower stretch of the cable toward the opposite post causes travel of the end one of the partitions with this stretch of the cable, until the stretch of the flexible connection 141 between the end partition and the 55 next partition is drawn taut, whereupon the second partition moves with the first one, and succeeding partitions are caused to travel in similar manner. The partitions are in suspended relation during their travel, being held above the surface of the race-track.

Just before the last one of the partitions it is desired to move to form the desired number of stalls reaches the position of the arm 60 148, the arm is placed in interfering relation

with said partition by release of the eye 158 from the hook 159. The turning of the winding sheave is continued until all of the flexible connections 141 have been made taut. The partitions hang suspended in vertical 70 positions.

The partitions are then dropped, as by rotation of the shaft 55 by means of the hand-wheel 71, for causing coaction between the lower ends of the partitions with the roadway, as by the sinking of the pointed ends at 75 the respective ends of the partitions into the roadway.

The stalls are then opened by release of one end of the respective chains 143 and the 80 horses admitted into the stalls, the latter chains being then reconnected at the rear of the horses for preventing backing of the horses out of the stalls. The horses' heads are directed toward the starting tape, and 85 the stirrups of the jockeys are located preferably at a level above the level of the top wall 175 of the lower section of the partitions, so as to have no interference between the horse or his rider and the partitions when 90 the start of the race is made. The partitions limit side-stepping and lateral shifting movement and rearing of the horses, and consequent interference between the horses, and 95 position the horses for proper starting of the race.

If the race is of such length as to end at or pass the stalls, the stalls are immediately, after the start of the race has been made, again shifted laterally out of the way of the 100 race-track, so as not to interfere with the race.

This is done by turning the handle 71 and thereby rotating the shaft 55 and raising the runway 44 for raising the partitions off the surface of the race-track and suspending the 105 partitions, pulling down the flexible connection 154 and connecting one of the eyes 158 with the hook 159, and rotating the handle 101 in reverse direction, for moving the stretch 125 of the cable in reverse direction, and pulling the end partition toward the space 131. Each of the carriers of the partitions acts on the neighboring carriage for moving all of the partitions out of range of the race-track and inside the rail 23, the bar 110 195 being preferably put in place, all of which may be done within a few seconds, so that by the time the horses arrive at the position of my improved starting device, the track will be clear for finish of the race in the usual way. 115 During such finish of the race, the end partition may be placed to fill the gap 132.

A suitable number of my improved starting devices may be arranged around the track, so as to provide starting points for 120 races of different distances which will end at the judges' stand and along the grand stand of the race course.

The operating means of my improved device may be placed at either side of the track.

and the partitions may be caused to travel crosswise of the track from one side or from both sides of the track. The partitions are quickly moved into place and quickly positioned crosswise of the track, but a few seconds being necessary to place the partitions to form the stalls or to remove the same off the race-course.

Having thus fully described my invention, 10 what I claim as new, and desire to secure by Letters Patent, is:

1. In a starting device for a race-track, the combination of a girder arranged to be positioned crosswise of the track, an overhead runway extending lengthwise of said girder, a series of stall-partitions supported by said runway, means for moving said partitions laterally on said runway, and means for raising and lowering said runway for coaction 15 of said partitions with said track.

2. In a starting device for a race-track, the combination of an overhead girder, an overhead runway in association therewith, a series of stall-partitions supported by said runway, flexible propelling means movable in opposite directions lengthwise of said girder, means connecting one of said partitions with said propelling means, and connecting means 20 between partitions for causing travel of successive partitions with said last-named partition and for spacing said partitions to form stalls.

3. In a starting device for a race-track, the combination of an overhead girder positioned crosswise above the race-track, an overhead runway in association therewith, a series of stall-partitions supported by said runway, a propelling means movable in opposite directions lengthwise of said girder, means connecting one of said partitions with said propelling means, connecting means between partitions for causing travel of successive partitions with said last-named partition and for spacing said partitions to form stalls, and means for lowering said partitions for coaction between said partitions and said race-track.

4. In a starting device for a race-track, the combination of an overhead girder, an overhead runway in association therewith, a series of stall-partitions supported by said runway, an endless cable comprising stretches movable in opposite directions lengthwise of said girder, means connecting one of said partitions with one of said stretches, connecting means between partitions for causing travel of successive partitions with said last-named partition and for spacing said partitions to form stalls, a shaft, and flexible connections 60 between said shaft and said runway whereby to raise and lower said partitions by rotation of said shaft.

5. In a starting device for a race-track, the combination of an overhead girder arranged 65 to be supported crosswise above the race-

track, an overhead runway extending lengthwise of said girder, a series of stall-partitions, carriers on said runway supporting said stall-partitions, means for moving said carriers on said runway, a shaft on said girder, flexible 70 connections between said shaft and said runway, means for connecting said flexible connections to said runway, and means for connecting said flexible connections to said shaft respectively at increasing radial distances 75 from the axis of said shaft whereby to cause lowering of said runway to unequal extents at its opposite ends for coaction of the lower ends of said partitions with an inclined race-track under said girder.

6. In a starting device for a race-track, the combination of an overhead runway, a series of stall-partitions suspended from said runway, flexible spacing connections between 80 said partitions whereby to laterally space said partitions to form stalls, means for causing lateral travel of an end one of said partitions along said runway, and a shiftable interfering part arranged to be placed in interfering relation with a partition, and arranged 85 whereby to limit lateral movements of said partitions for spaced relation between said partitions.

7. In a starting device for a race-track, the combination of an overhead runway, a series 90 of stall-partitions suspended from said runway, said respective stall-partitions comprising a lower longer section extending lengthwise of the race-track, a vertical shorter section above one end of said lower longer section, and suspending means at the inner end of said vertical section for arranging the center of gravity of said partition directly below said suspending means.

8. In combination, a race-track provided 105 with a rail, an overhead runway extending overhead above said track and beyond said track outside said rail, and a series of stall-partitions supported by said runway, said partitions movable laterally on said runway 110 crosswise of said track and outside said rail, said rail provided with a gap through which said partitions are arranged to move to positions above said track and outside said rail.

9. In combination, a race-track provided 115 with a rail, an overhead runway extending overhead above said track and beyond said track outside said rail, a series of stall-partitions supported by said runway, said partitions movable laterally on said runway crosswise of said track and outside said rail, said rail provided with a gap through which said partitions are arranged to move to positions 120 above said track and outside said rail, and means in substantially the vertical plane of 125 said rail for limiting lateral movements of said partitions.

In testimony whereof, I have hereunto signed my name.

RICHARD C. STEWART.
